UNITED STATES PATENT OFFICE.

JAMES G. MACLAREN, OF SYRACUSE, NEW YORK, ASSIGNOR, BY MESNE ASSIGNMENTS, TO THE LAMSON COMPANY, OF SYRACUSE, NEW YORK, A CORPORATION OF MASSACHUSETTS.

RECEIVING TERMINAL FOR CONVEYER SYSTEMS.

Original application filed March 26, 1920, Serial No. 369,084. Renewed March 9, 1925. Divided and this application filed March 11, 1925. Serial No. 14,694.

To all whom it may concern:

Be it known that I, JAMES G. MACLAREN, a citizen of the United States of America, and resident of Syracuse, in the county of Onondaga and State of New York, have invented new and useful Improvements in Receiving Terminals for Conveyer Systems, of which the following is a specification.

This invention relates to article receiving apparatus for conveyer systems and more particularly to apparatus for receiving carriers at a terminus, for example, the central station of a pneumatic despatch system, the present application being a division of my pending application, Serial No. 369,084, for carrier distributor, filed March 26, 1920, renewed March 9, 1925.

The principal object of the present invention is to provide receiving apparatus having automatically actuated means for delivery of carriers alternatively to one or another of two attendants, depending upon the number of carriers remaining in the receptacle provided at the station of one such attendant.

One embodiment of this invention is illustrated by way of example in the accompanying drawing which shows a side elevation of the carrier receiving apparatus in normal position, certain parts being in section.

Referring to the drawing the numeral 1 designates a hopper pivoted at the point 1^a remote from and above its center of gravity. A fixed bracket 2 carries the pivots 1^a of the hopper and supports the hopper beneath a delivery terminal, for example, a tube 3 adapted to deliver carriers into the upper end of the hopper. The hopper is provided with an extension or guide 4 preferably of tubular form which is adapted to guide carriers deposited in the hopper 1 to the upper end of a fixed receptacle 5, the latter preferably being of tubular construction open at its upper end and having a shelf or stop 5^a at its lower end.

Preferably this receptacle is inclined as indicated in the drawing, and an opening 5^b is provided in its upper side wall adjacent to its lower end to permit a carrier resting upon the shelf 5^a to be withdrawn from the receptacle. If the first carrier 6 which

comes to rest upon the shelf 5^a is not immediately removed, successively arriving carriers will take the positions indicated at 7 and 8, respectively, the length of the receptacle 5 being such that the last or uppermost carrier of such a series will rest against the inwardly projecting nose 9 of a lever 9^a pivoted at 10 upon the upper end of the receptacle.

Normally this lever occupies the full line position shown in the drawings, and when in this position a valve 11, which is carried by the lever, closes the entrance to a chamber 12 in a boss 12^a projecting from the wall of the receptacle 5. The lever 9^a is so counterweighted that when there is no carrier occupying the position 8 the lever will remain in the full line position closing the chamber 12 as just described. If, however, a carrier occupies the position indicated in dotted lines at 8 the weight of its upper end, resting against the nose 9 of the lever, swings the latter outwardly and opens the chamber 12 to the atmosphere.

The chamber 12 communicates through tubes 13 and 14 with one end 14^a of the cylinder 15 of a pneumatic motor and by means of a tube 13^a, needle valve 16, and tube 17 with a chamber within which there is maintained a pressure substantially equal to that maintained in the pneumatic despatch system of which the apparatus forms a part. For present purposes the system is assumed to be of the vacuum type and the chamber with which the tube 17 communicates may be assumed to be the exhaust header 18 of such a system. This exhaust header 18 also communicates with the opposite end 14^b of the cylinder 15 by means of a tube 19.

A piston 20 slides within the cylinder 15 and the piston rod 21 is connected by a link 22 to the lower end of the guide member 4 of the hopper, so that movement of the piston away from its normal position will swing the hopper 1 and the guide 4 to the position 23 indicated in dotted lines.

When the valve 11 is opened by the pressure of a carrier occupying the position 8, air at atmospheric pressure enters the chamber 12 and passing through the tubes 13 and 14 enters the cylinder 15. The needle valve 16 is so adjusted that air can enter the cylinder through the pipe 14 more rapidly than

it is exhausted through the pipe 17. The pressure at the opposite side of the piston is thus unbalanced and the piston moves toward the end 14^b of the cylinder, thus 5 swinging the hopper and guide to the dotted position 23, where they will remain until the valve 11 is closed by the removal of a carrier from the position 8. So long as the guide 4 remains in the position 23, arriving carriers 24 will be diverted from the receptacle 5 and may be received upon a suitable chute, shelf, or moving belt 25 where they may be cared for by an attendant or conveyed to a remote point of discharge. 10 15

When the lowermost carrier 6 is removed from the receptacle 5, the upper carriers 7 and 8 will drop, thus releasing the lever 9 and permitting the valve 11 to close. The 20 pressure upon opposite sides of the piston will now slowly equalize through the valve 16 and the hopper 1 and the guide 4 will fall back to normal position under the action of gravity, thus restoring the piston to 25 its original position.

The device thus described is particularly useful where carriers are likely to arrive too rapidly to be cared for by an attendant stationed at the receptacle 5, or when, as may 30 sometimes happen, it is necessary for such attendant to leave her station for an interval. In either case surplus carriers arriving through the tube 3 will be diverted from the receptacle 5 and may be conveyed to some other point where they will be 35 cared for by another attendant.

I claim:

1. In a carrier receiving apparatus, a receptacle for carriers, a movable guide normally positioned to deliver arriving carriers to said receptacle, and power actuated means responsive to the presence of a carrier occupying a predetermined position in the receptacle to displace said guide from its 40 normal position whereby later arriving carriers will be diverted from the receptacle. 45

2. In a carrier receiving apparatus, a receptacle for carriers, a pivotally suspended guide normally positioned to deliver arriving carriers to the receptacle, a fluid motor for swinging the guide away from its normal position, and means actuatable by a carrier occupying a predetermined position in the receptacle to admit pressure fluid to the 50 motor and thereby to swing the guide out of its normal position and terminate delivery of carriers to the receptacle. 55

3. In a carrier receiving apparatus, a receptacle for carriers, a pivotally suspended 60 guide normally positioned to deliver carriers to a receptacle, a pneumatic motor having a piston member connected to said guide and adapted to swing the latter upon its pivot, a valve controlling the operation of said motor, and means actuatable by a car- 65

rier occupying a definite position in the receptacle for opening said valve whereby to start the motor and thereby to swing said guide upon its pivot.

4. In a carrier receiving apparatus, a receptacle for carriers, a pivotally suspended guide normally positioned to deliver carriers into said receptacle a pneumatic motor comprising a cylinder having a piston therein, means connecting the piston to the guide, a tube communicating with one end of said cylinder, a second tube communicating with the opposite end of said cylinder, means normally maintaining sub-atmospheric pressure in said tubes, a valve for admitting air at 70 atmospheric pressure to one of said tubes, and means actuatable by a carrier occupying a predetermined position in the receptacle to open said valve, whereby the air pressure upon opposite sides of the piston will be unbalanced and the piston will move the guide 75 out of its normal position with relation to the receptacle. 80 85

5. In a carrier receiving apparatus, for a vacuum pneumatic despatch system, a fixed receptacle for carriers, a pivotally suspended guide normally positioned to deliver carriers to the receptacle, a pneumatic motor comprising a cylinder and a piston sliding therein, means connecting the piston to the 90 guide for swinging the latter from its normal position relative to the receptacle, a tube communicating with one end of said cylinder, a second tube communicating with the opposite end of said cylinder, means for 95 transmitting the sub-atmospheric pressure of the system to said tubes, a normally closed valve for admitting atmospheric pressure to one end of the cylinder, and means actuatable by a carrier occupying a predetermined position in the receptacle for opening said valve to admit air to one end of the cylinder, thus actuating the piston and thereby displacing the guide relatively to the receptacle. 100 105

6. In a carrier receiving apparatus, a receptacle for carriers, a pivotally suspended guide normally positioned to deliver carriers to the receptacle, a pneumatic motor comprising a cylinder and a piston therein, means connecting the piston to the guide, a tube communicating with one end of the cylinder, a second tube communicating with the opposite end of the cylinder, means for establishing sub-atmospheric pressure in said tubes, a normally closed valve for admitting 110 atmospheric air to one of said tubes, and a weighted lever normally retaining said valve in closed position, said lever having a part engageable by a predetermined one of a series of carriers resting in the receptacle 115 whereby to open said valve and admit air to the motor thereby moving the piston and displacing the guide so as to terminate delivery of carriers to the receptacle. 120 125

7. In a carrier receiving apparatus, a re- 130

- ceptacle for carriers, a pivotally suspended guide normally positioned to deliver carriers to the receptacle, a pneumatic motor comprising a cylinder and a piston therein,
5 means connecting the piston to the guide, a tube connected to one end of the cylinder, a second tube connected to the opposite end of the cylinder, each of said tubes communicating with a chamber in which sub-atmospheric pressure is maintained, a needle valve in one of said tubes restricting the passage between the cylinder and said exhaust chamber, a normally closed valve for admitting atmospheric air to that end of the cylinder
10 with which said last named tube communi-
cates, and means actuatable by a carrier occupying a definite position in the receptacle for opening said valve to admit air to said one end of the cylinder, whereby to displace the piston and move the guide from its 20 operative position relatively to the receptacle, said air admission valve closing automatically when said carrier is removed from such definite position in the receptacle, thereby permitting the piston and guide to 25 return to normal position.

Signed by me at Syracuse, New York, this 28th day of February 1925.

JAMES G. MACLAREN.
